(57) **CLAIM**

The ornamental design for an incontinence pad with receptacle, as shown and described.

DESCRIPTION

FIG. 1 is an isometric view of an incontinence pad with receptacle, showing my design;

FIG. 2 is a top view thereof;

FIG. 3 is a bottom view thereof;

FIG. 4 is a front elevational view thereof, the rear elevational view being substantially identical thereto; and,

FIG. 5 is a left side elevational view thereof, the right side elevational view being substantially identical thereto.
